UNITED STATES PATENT OFFICE.

WALTER E. PROSSER, OF LOUISVILLE, KENTUCKY, AND ALBERT E. HIGGINS, OF BUFFALO, NEW YORK.

PORTABLE STEAM-GENERATOR.

1,395,973.

Specification of Letters Patent.

Patented Nov. 1, 1921.

Application filed July 19, 1920. Serial No. 397,221.

To all whom it may concern:

Be it known that we, WALTER E. PROSSER and ALBERT E. HIGGINS, citizens of the United States, residing at Louisville and Buffalo, in the counties of Jefferson and Erie and States of Kentucky and New York, respectively, have invented certain new and useful Improvements in Portable Steam-Generators; and we do hereby declare the following to be a full, clear, and exact description of the invention, such as will enable others skilled in the art to which it appertains to make and use the same.

Our invention relates to improvements in portable devices for generating steam intended for use in warming up or thawing out the radiators, engines, etc., of automobiles or stationary internal combustion engines, or for other purposes where it is desired to supply a warming fluid medium, such as steam, for the like or kindred purposes.

More or less trouble is encountered even in closed city garages with the freezing up of the engines or radiators of automobiles, auto trucks, or the like, and this trouble is very largely increased where the vehicles carrying the engine, radiators, or the like are parked in the open in cold climates, and where it is difficult to secure a sufficient supply of hot water ordinarily used for the thawing out purposes.

Our invention is primarily intended to form a part of a military train, whether of supplies, ordnance, or artillery, but is capable of use for private purposes.

Our invention will be more fully understood after reference to the accompanying drawings, in which like parts are indicated by similar reference symbols throughout the several views, and in which:—

Figure 1 is a central vertical section through the axis of the container, the section being along the line 1—1 of Fig. 2, and parts being shown in elevation; and

Fig. 2 shows a section along the line 2—2 of Fig. 1 and looking down.

A represents a cylindrical container separated by the partition A⁰ into a large steam chamber A' and a smaller water chamber A². Below the raised bottom A⁶ of the water chamber is the heating chamber A³, closed by the hinged door B, hinged as at b and fastening as at b' when in the closed position, see Fig. 2. In this chamber A³ the

heating coil D is mounted, connected by the water supply pipe C to the water chamber, and the passage of water through this pipe is controlled by the valve e. The heating coil opens into the steam chamber A², 60 as at d.

Mounted in the burner chamber A³ is any suitable heating device, such as the blow torch E which may be removed or inserted as desired, and in transport is held in place 65 by the door B; but when in use this door B should be left open as shown in dotted lines in Fig. 2.

The container A is provided with a suitable bottom A⁴, preferably raised slightly 70 above the bottom of the container, and also with a dome-shaped cap A⁵, and in this cap A⁵ a suitable opening, closed by the filling plug F, is provided, and through this filling plug the stem f of an ordinary air 75 valve may be mounted, such, for instance, as is used in inflating automobile tires, or the like.

A suitable delivery pipe G for carrying off steam is provided, which may be controlled by the valve g, and delivers steam through a suitable flexible hose G' to the desired point.

H represents a check valve connecting the chambers A' and A² which may be of the 85 form of a flap, or other suitable form of check valve, opening from the chamber A' into the chamber A².

A drain opening may be provided near the bottom of the steam chamber, closed by 90 the plug I, for the purpose of drawing off any condensed water that may be accumulated therein.

A suitable safety valve K, and a steam gage L, may be provided for the steam chamber if desired. In order to provide for the convenient transportation of the device, we provide a handle M, preferably insulated as at m, from the body of the container so that the handle will not get too hot for convenient use.

If desired, suitable heat insulating material, such as felt, or the like may surround the body of the container, but such expedient is well known in the art and may be 105 omitted or added if desired.

To use the device, the water chamber A² is partly filled with water, the plug F inserted, and air is pumped in under a few pounds of pressure, tending to force the 110

water in the tank downward, and also to close the check valve H. The valve g being closed, open the door B, partly open the valve e and ignite the burner. Steam will be rapidly generated in the heating coil D and will accumulate in the steam chamber A'. A small part of the steam, of course, will be turned into condensed water, but the balance may be drawn off through the hose 10 G' to the point of consumption by opening the valve g. When the pressure in the steam chamber A' exceeds the air pressure in the water chamber A², the check valve H will open and the pneumatic pressure will be 15 come balanced in the system, but the weight of the column of water will cause the liquid to flow continuously through the heating coil as it becomes converted into steam.

After warming up one engine, the apparatus 20 may be moved to another engine by simply closing the door, lifting it by the handles; or by having the hose long enough, a number of engines may be warmed consecutively; or there may be a series of delivery 25 nozzles for the steam, each provided with a hose whereby the same apparatus may be simultaneously used to warm up a number of engines.

By having the parts made of light strong 30 metal, such as sheet steel, and having the water chamber comparatively small with regard to the steam chamber, a comparatively light device may be provided, weighing, for instance, approximately sixty (60) pounds, 35 which is highly efficient for the purposes stated; but which may be readily and conveniently transported from place to place and quickly put into and out of operation.

Compressed air may be supplied in any 40 convenient way, as by the ordinary hand pump P used for pumping up the tires of a bicycle or automobile, and we prefer to use compressed air both to cause the water to feed quickly at the start, and to keep the 45 check valve H closed, thereby preventing the water supply from running into the steam chamber should the container be turned on its side in transport, with the water chamber up; but the device may be 50 used without the air pressure if the check valve H is properly set or controlled.

If desired the burner and hose may be carried separately and only put in place at the time of use. Also the pressure gage L 55 may be made detachable to avoid injury in transportation.

By having the container of cylindrical shape it may be readily and cheaply made, and great strength may be secured for a 60 correspondingly small weight of metal.

It will be obvious that various modifications might be made in the herein described apparatus and in the construction, combination and arrangement of parts which could 65 be used without departing from the spirit

of our invention; and we do not mean to limit the invention to such details except as particularly pointed out in the claims.

Having thus described our invention what we claim and desire to secure by Letters 70 Patent of the United States is:

1. A portable steam generator comprising a cylindrical container provided with a longitudinal partition separating it into a steam chamber on one side of said partition and a heating chamber and a water chamber above the same on the other side of said partition, said water chamber being separated from said heating chamber by a transverse partition forming the bottom 75 of said water chamber and the said heating chamber being provided with a lateral opening through the shell of said container, a heating coil mounted in said heating chamber and opening at its upper end into said steam chamber, a feed pipe for water connecting said water chamber with the lower end of said heating coil, means for controlling the flow of water through said feed pipe, means for carrying off the steam from said steam chamber, and a check valve opening from said steam chamber into the upper portion of said water chamber.

2. A portable steam generator comprising a cylindrical container provided with a longitudinal partition separating it into a steam chamber on one side of said partition and a heating chamber and a water chamber above the same on the other side of said partition, said water chamber being separated from said heating chamber by a transverse partition forming the bottom of said water chamber and the said heating chamber being provided with a lateral opening through the shell of said container, a heating coil mounted in said heating chamber and opening at its upper end into said steam chamber, a feed pipe for water connecting said water chamber with the lower end of said heating coil, means for controlling the flow of water through said feed pipe, means for carrying off the steam from said steam chamber, means for supplying air under pressure to the upper portion of said water chamber and a check valve opening from said steam chamber into the upper portion of said water chamber.

3. A portable steam generator comprising a cylindrical container provided with a longitudinal partition separating it into a steam chamber one side of said partition and a heating chamber and a water chamber above the same on the other side of said partition, said water chamber being separated from said heating chamber by a transverse 120 partition forming the bottom of said water chamber and the said heating chamber being provided with a lateral opening through the shell of said container, a curved door hinged to said container and closing said 125

- opening and forming when closed a continuation of said cylindrical shell, a heating coil mounted in said heating chamber and opening at its upper end into said steam chamber, a feed pipe for water connecting said water chamber with the lower end of said heating coil, means for controlling the flow of water through said feed pipe, means for carrying off the steam from said steam chamber, means for drawing off the condensed water from said steam chamber, and a check valve opening from said steam chamber into the upper portion of said water chamber.
4. A portable steam generator comprising a cylindrical container provided with a longitudinal partition separating it into a steam chamber on one side of said partition and a heating chamber and a water chamber above the same on the other side of said partition, said water chamber being separated from said heating chamber by a transverse partition forming the bottom of said water chamber and the said heating chamber being provided with a lateral opening through the shell of said container, a curved door hinged to said container and closing said opening and forming when closed a continuation of said cylindrical shell, a heating coil mounted in said heating chamber and opening at its upper end into said steam chamber, a feed pipe for water connecting said water chamber with the lower end of said heating coil, means for controlling the flow of water through said feed pipe, means for carrying off the steam from said steam chamber, means for drawing off the condensed water from said steam chamber, means for supplying air under pressure to the upper portion of said water chamber, and a check valve opening from said steam chamber into the upper portion of said water chamber.
5. A portable steam generator comprising a cylindrical container provided with a longitudinal partition separating it into a steam chamber on one side of said partition and a heating chamber and a water chamber above the same on the other side of said partition, said water chamber being separated
- from said heating chamber by a transverse partition forming the bottom of said water chamber and the said heating chamber being provided with a lateral opening through the shell of said container, a handle secured to said cylindrical shell, a heating coil mounted in said heating chamber and opening at its upper end into said steam chamber, a feed pipe for water connecting said water chamber with the lower end of said heating coil, means for controlling the flow of water through said feed pipe, means for carrying off the steam from said steam chamber, means for drawing off the condensed water from said steam chamber, and a check valve opening from said steam chamber into the upper portion of said water chamber.
6. A portable steam generator comprising a cylindrical container provided with a longitudinal partition separating it into a steam chamber on one side of said partition and a heating chamber and a water chamber above the same on the other side of said partition, said water chamber being separated from said heating chamber by a transverse partition forming the bottom of said water chamber and the said heating chamber being provided with a lateral opening through the shell of said container, a handle secured to said cylindrical shell, a heating coil mounted in said heating chamber and opening at its upper end into said steam chamber, a feed pipe for water connecting said water chamber with the lower end of said heating coil, means for controlling the flow of water through said feed pipe, means for carrying off the steam from said steam chamber, means for drawing off the condensed water from said steam chamber, means for supplying air under pressure to the upper portion of said water chamber, and a check valve opening from said steam chamber into the upper portion of said water chamber.

In testimony whereof we affix our signatures.

WALTER E. PROSSER.
ALBERT E. HIGGINS.
